UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP AND PUMPING SYSTEM.

1,385,061.

Specification of Letters Patent. Patented July 19, 1921.

Application filed July 27, 1917. Serial No. 183,094.

To all whom it may concern:

Be it known that I, BURTON S. AIKMAN, a citizen of the United States, residing at Milwaukee, in the county of Milwaukee and State of Wisconsin, have invented a certain new and useful Improvement in Pumps and Pumping Systems, of which the following is a full, clear, concise, and exact description, reference being had to the accompanying drawings, forming a part of this specification.

My invention relates to pumps and pumping systems particularly of that class known as faucet controlled systems.

15 This invention provides a pumping system employing a single cylinder pump operated from a source of compressed air or other motive fluid to raise water or other liquid from a well to a consumption system as, for instance, to the water pipes and faucets of a residence without the interposition of a storage tank. In this type of system the well itself is the only storage tank and the water is pumped therefrom 20 in accordance with the demand, as indicated by opening the faucets or other outlets of the system.

In accordance with my invention I provide an auxiliary pumping means in connection with the single pump cylinder which auxiliary pumping means is located at the top of the well and which serves to equalize the pressure and consequently the flow.

Heretofore it has been customary to provide the pump cylinder with valves in the head of the cylinder and to lower the cylinder with valves and all down into the well. According to my present invention the valves which control the admission and exhaust of the motive fluid to the pump are located at the head of the well and are preferably connected with the auxiliary pumping means. Consequently better attention can be given to the working parts of the pump and the valves and in the case of repairs required by the valves much less work and difficulty is involved.

In accordance with my invention the valve located at the head of the well and operated in connection with the auxiliary pumping means may directly control the admission and exhaust of motive fluid to the pump or may control the same through a relay

or intermediate operating means. Thus the valve may be relatively small and may 55 be the same for all capacities of pumps, the dimensions of the pump and operating means being varied to secure greater capacity.

It will be apparent from the detailed description and the appended claims that there are many aspects of my invention which are novel in themselves, and that my invention provides certain fundamental combinations of parts which are novel in this art and 60 which may appear in embodiments superficially quite different from the particular embodiment which I have herein described and illustrated.

In order to apprise those skilled in the 70 art how to practise my invention, I shall describe in detail a specific embodiment of the same in connection with the accompanying drawings which form a part of the present specification.

75 Figure 1 is a diagrammatic view of a system embodying my invention in which the valve at the head of the well controls directly the admission and exhaust of motive fluid to and from the working cylinder of 80 the pump;

Fig. 2 is a fragmentary diagrammatic view indicating the modified structure employed where the valve at the head of the well is a master valve which works through 85 a relay for controlling the admission and exhaust of motive fluid to and from the working cylinder;

Fig. 3 is a diagrammatic illustration of a modification in which the valve at the 90 head of the cylinder also serves as a master valve and operates through a body of liquid instead of a solid stem to work a valve which controls the admission and exhaust of motive fluid to and from the pump 95 cylinder;

Fig. 4 is a sectional view, with parts broken away, showing the details of the system indicated in the diagram of Fig. 2;

Fig. 5 is a section of the master valve, 100 taken on the line 5, 5, of Fig. 4;

Fig. 6 is a cross-sectional view of the pump cylinder showing the connections and valves for the same, showing also the control valve which is operated through the medium of a body of liquid; and 105

Fig. 7 shows a rear elevation of said valve and Fig. 8 shows a section of the valve taken on the line 8, 8, of Fig. 6.

The cylinder 1 is lowered into the water 5 of the well, this cylinder being sufficiently submerged so that when the exhaust valve is opened the water will flow into and fill the cylinder speedily.

Air is supplied from any suitable source, 10 such, for instance, as the compressed air tank 2, for raising the water from the pump cylinder 1. The tank 2 may be automatically recharged by suitable air compressing means or it may be periodically recharged 15 as may be desired. At the head of the well I provide the auxiliary pumping means 3 which is connected to the pump cylinder 1 by means of the water pipe 4 which forms a pipe for the discharge of pump 1. The 20 auxiliary pumping means 3 is connected by means of a discharge pipe 5 to the consumption system, such as the water pipes and faucets of a residence or the like.

A master valve 6 is also located at the 25 head of the well and this valve is operated in connection with the auxiliary pumping means 3 to control the admission and exhaust of motive fluid to and from the pump cylinder 1. For this purpose an air pipe 7 leads from the valve 6. This pipe 7 may be directly connected to the pipe 8 which supplies air to the pump cylinder 1, or it may be connected as by means of the pipe 9, in Fig. 2, to an operating or motor element 10 which in turn controls a valve 11 that governs the admission of motive fluid to the pump and its exhaust therefrom.

The auxiliary pumping means 3 is of a capacity suitable to receive about half the 40 discharge of the pump 1, the rest of the discharge going directly through the pipe 5 to the consumption system. As the auxiliary pumping means 3 operates against a less head than does the pump 1, air is supplied at 45 a reduced pressure by means of the reducing valve 11, auxiliary tank 12 and pipe 13 to the auxiliary pumping means for the purpose of maintaining the flow in the discharge pipe 5 during the time that the pump 50 1 is filling. The auxiliary pumping means 3 and the tank 12 in reality constitute an air spring of large capacity which is adapted to operate the master valve 6.

The construction of the valve 6 is shown 55 in Figs. 4 and 5.

The diaphragm chamber 3 comprises two hollow cylinders 14 and 15 clamped together at their peripheries with a flexible diaphragm 16 gripped between them. This 60 flexible diaphragm is provided at its center with a metallic piston consisting of two similar parts 17 and 18 clamped together at their edges. The part 17 is provided with a valve seat 19 which is adapted to engage the 65 valve opening 20 in case of derangement of

the system. The piston member 18 is provided with a projecting stem 21 which is adapted to engage an operating rod 22, shown in dotted lines in Figs. 4 and 5. This rod 22 is provided with a groove engaged by 70 the arm 23 of the operating lever which operates the movable valve body 24. A suitable casting 25 is formed integral with the cylinder member 15 and provides the necessary connections and support for the structure of the valve 6.

The arm 23 is attached to a rock shaft 26 which has the valve operating arm 27 connected thereto. The valve operating arm 27 is forked at its end to embrace the reduced 80 portion 28 of the valve rod 29. The reduced portion 28 lies between two collars 30 and 31 which permit of considerable play before the valve stem 29 and the valve body 24 are actually moved.

The shaft 26 is provided with another arm 32 to which is connected one end of the spring 33. The other end of the spring 33 is secured to the stationary pin 34. This spring is of sufficient strength to give the 90 valve a positive snap action. It is to be noted that the operating rod 22 which is engaged by the boss 21 is not connected thereto. The valve casing 36 is provided with an exhaust opening 37 and admission opening 38 95 communicating with the pipe 39, which leads to the main reservoir 2 and an opening 40 which is connected to the pipe 7. This pipe 7 leads either directly to the pump cylinder 1 where the valve acts directly to control the admission and exhaust of motive fluid to the pump or leads to the controlling element 10 and this in turn operates a valve which controls the admission and the exhaust of the pump cylinder 1. The admission opening 38 is provided with a port 42 which is adapted to be closed by the yielding seat 43 on the valve body 24. The exhaust opening 37 communicates with the body of the valve through a port 44 which is adapted to be 100 closed by the yielding face 45 on the valve body 24. It can thus be seen that when the valve body 24 is moved downward it closes off the port 44 and opens the port 42. This permits air from the reservoir to enter 110 through the pipe 39 and pass through the port 42 to the pipe 7 and from there either to the pump cylinder 1 or to the operating element 10, as will be explained later. When the valve is moved in the opposite direction 120 the port 44 is opened and the pipe 7 thus communicates with the atmosphere.

The pump 1 comprises a barrel member 47 which is formed of a piece of tubing of the proper diameter. A head member 48 is attached to the upper end of the barrel 47 and a foot member 49 is attached to the lower end of the barrel member 47. This is accomplished by means of a piece of pipe 50 which is connected to the head 48 and to a valve 130

cage 51 which is connected to the foot by means of the central bolt 52. The head member 48 has a passage 53 communicating with the water discharge pipe 4 which leads 5 to the top of the well and communicates at its other end with the pipe 50. The pipe 50 in turn communicates with the interior of the valve cage 51. The valve cage 51 in- 10 closes the check valve 54 which communicates with the lower part of the pump cylinder 47 by way of the passages 55.

The foot member 49 is provided with inlet ports 56 which coöperate with the foot valve 57. A conical screen 58 covers the 15 bottom of the foot member 49 and prevents the entry of foreign matter to the pump cylinder.

The cylinder head 48 is provided with an opening or passageway 59 which communicates with the interior of the barrel 47 and with an air supply pipe, namely the air supply pipe 8 of Fig. 1, or the air supply pipe 60 of Figs. 2 and 4, or the air supply pipe 61 of Figs. 3 and 6.

In the diagram of Fig. 1 the valve 6 admits air to the cylinder 1 and permits exhaust from the cylinder 1. This arrangement is entirely satisfactory when the capacity of the pipes 7 and 8 is relatively small. If, however, the well from which the water is pumped is relatively deep so that the cubical contents of the pipes 7 and 8 is considerable, it would be quite inefficient to exhaust this amount of air for each stroke. In order to avoid this loss of air I provide a valve near the head of the pump and operate it by means of a cylinder and piston, or some other operating element located at the head of the well or at any other 35 suitable position. The valve 6 then operates purely as a master valve and the control is relayed through the operating elements to the control valve.

Figs. 2 and 4 illustrate such a system where the master valve 6 operates through the operating element 10 to work the controlling valve 11. In this case the controlling element 10 consists of a small cylinder 63 communicating by way of the pipe 64 40 with the pipe 7. The cylinder 63 is provided with a lining 65 that has a valve seat 66 at the upper end as will be explained later. A movable piston member 67 is adapted to slide in the cylinder 63. A rod 68 is connected by means of the spring connection 69 with the piston 67 and extends down through the pipe 70 to the controlling valve body 71 which preferably is located adjacent the head of the pump 1.

The pipe 70 communicates by means of a T connection 72 with the pipe 73 which is connected in turn either directly to the tank 2 or to one of the pipes such as 74 communicating with the compressed air tank 2.

It can thus be seen that the piston 67 is

subjected on the one side to air from the pipe 7 and on the other side to air through the pipe 73, both at substantially the same pressure. The piston 67 is provided at its upper surface with a valve seat 75 adapted 70 to engage the seat 66 to prevent leakage past the piston 67 when the piston is moved to its uppermost position.

It will be noted that when the piston 67 seats against the valve seat 66 the effective 75 area of the piston on its upper surface is reduced so that when live air is admitted on the upper side of the same the piston will first be broken away from the seat and then moved down with a snap action. The 80 spring 69 performs a dual function. It permits the admission valve 85 to be closed before the piston strikes the seat 66 so that the admission valve is moved to its seat by the full pressure of the fluid pressure on 85 the lower side of the piston and then the piston is held in its upper position against the seat 66 with the spring 69 under tension. Hence, as soon as the piston moves away from its seat 66, the spring pulls it 90 away quickly letting the air equalize suddenly so that the weight of the parts and the pressure of the air on the admission valve 85 moves the valve structure 84 down with a snap to close the exhaust valve 89. 95 The spring also aids on the upward motion of the piston 67 to throw the exhaust valve clear of its seat after it is once pulled away from its seat against the force of the compressed air which holds it on seat while 100 pressure is on the pump chamber. The upward throw of the spring also snaps the admission valve 85 shut by the same action.

The controlling valve body 71 comprises a substantially cylindrical body provided 105 with a transverse exhaust passage 76 and an axial passage 77 which communicates by way of the reduced portion 78 with the pipe 60 leading to the cylinder head 48 and the interior of the pump 1. The portion 78 of 110 the valve body 71 and the pipe 60 are joined together by a union which has a flared funnel shaped member 80 at its upper edge for directing the reduced part 78 of the valve body 71 to the threaded part of the union, 115 thus if any derangement of the valve within the valve body 71 should occur the same may be unthreaded at the union 79 and raised to the surface. Thereafter the reduced portion 78 may be threaded into the 120 union because of the funnel shaped guiding member 80 which directs it to the threaded portion. The funnel shaped member 80 is of substantially the diameter of the pump 1 and embraces the water pipe 4, hence it is 125 easy to cause engagement of the screw threads.

The valve body 71 has a head member 81 provided with a valve port 82. A valve guiding member 83 passes through the port 130

82 and guides the valve body 84 in opening and closing said port. The guide 83 is connected to the valve rod 68 which, as previously explained, is connected to the piston 67. 5 The valve member 84 comprises an outer shell having a yielding seat 85 at its upper surface. A screw plug 86 enters the bottom of the shell of the valve member 84 and embraces the cylindrical part 87 which has an 10 annular shoulder 88 at its upper end. The cylindrical part 87 slides in the ring 86. A yielding valve face 89 co-operates with the exhaust port 90. This valve face is secured to the cylindrical member 87. It can be 15 seen that the cylindrical member 87 with its shoulder 88 forms a lost motion connection with the rod 68 through the various parts previously described.

The operation of the system shown in Fig. 20 4 is as follows:

Air is supplied under suitable pressure by way of the inlet pipe 39 to the master valve 6. Air at reduced pressure is admitted by way of the reducing valve 11 to the tank 12 25 which communicates by way of the pipe 13 with the auxiliary pumping device 3. Assuming that the consumption system is open to permit water to escape from the pipe 5 the first movement will be that of the dia- 30 phragm 16 under the pressure of the air in the tank 12 driving the water out of the cylinder 14. When the piston member 18, 19, has moved sufficiently far to the left, as seen 35 in Fig. 4, the valve member 24 will be operated to open the admission ports to permit compressed air to enter the pipe 7 and pass through the operating cylinder 10 driving the piston 67 and rod 68 downward, thereby 40 opening the valve 82, 85 and closing the valve 89, 90. Closing the valve 89, 90, shuts off the exhaust passage 76 and opens the 45 compressed air port 82, permitting air from the pipe 73 to pass down by way of the pipe 60, to the pump 1 to drive the water out of the pump through the pipe 4. Part of the 50 discharge of the pump flows out of the pipe 5 by way of the consumption system and a part of the water is accumulated in the auxiliary pumping device 3. This accumulation 55 of water in the cylinder 14 moves the piston member 18, 19 to the right, as shown in Fig. 4, causing the valve to be snapped into the opposite position, closing the inlet port and then opening the exhaust port 44 thereby permitting the air in the pipes 7, 64, 60 to exhaust. The pressure in the pipe 70 is substantially full tank pressure and this operates with greater effective area upon the bottom of the piston 67 than upon the valve member 84 at the lower end. Consequently the piston 67 and rod 68 begin to move upward carrying with them the guide 83 and the valve seat 85 but due to the lost motion connection moving at first independently of 65 the exhaust valve 89. However, just before

the admission port 82 is closed by the valve 85, the exhaust valve 89 is jerked off of its seat and the exhaust port 90 is opened. This action is aided by the spring 69 which permits the piston 67 to move ahead of the rod 68 so that the last part of the movement of the valve 85 to closed position and the valve 89 to open position is attributed to the action of the spring 69 independently of the movement of the piston 67 at that time. The difference in area between the bottom of the piston 67 and the area of the valve 85 is such that the valve readily remains in closed position. 70 75

It is further to be noted that the guide 83 comprises a round rod which substantially closes off the valve port 82 just before the valve 85 engages the port 82, thus preventing any appreciable leakage of air even if the movement of the exhaust valve 89 should be slow, delaying the closing of the valve 85. 80 85

During the time that the exhaust port 90 is open the air escapes from the pump 1 and the space in the pump is filled by incoming water. During the filling period, which is 90 relatively brief, the auxiliary pumping device 3, which might be termed an accumulator, forces the water, contained between the cylinder 3 and the piston 19 with its dia- 95 phragm 16, out by way of the pipe 5 to the consumption system. Thus a steady flow of water is maintained at the faucets or other points of consumption.

The system indicated diagrammatically in Fig. 3 is substantially the same as that indicated in Fig. 2. In this system instead of employing a pump rod, such as the one shown at 68 in Fig. 4, to work between the head and the bottom of the well, I employ a pipe 91 filled with a body of liquid 92 100 which transmits the pressure of the air from the pipe 7 to a combined operating unit and valve 90 at the bottom of the well. A compressed air pipe 93 which like the pipe 73 is adapted to be connected to the tank 2, 105 either directly or to one of the pipes, such as 74, leads down to the operating valve member 90. The details of this operating and valve element 90 are shown in Figs. 6, 7 and 8. The operating part of the element com- 110 prises a cylinder 94 closed off by a dia- phragm 95 and piston 96. The liquid 92 which is incompressible serves merely as a motion transmitting means between the air in the pipe 91 and the diaphragm or piston 96. The body of the device is provided with an air inlet 97 to which compressed air is admitted, a cylinder connection 98 leading to the pump cylinder by way of the pipe 61 and outlet 99 for the exhaust. The cylinder connection 98 communicates with the central portion 100 of the valve body 101. The air inlet 97 communicates at one end by way of the inlet port 102 with the central part 100. This port 102 is adapted to be 115 120 125 130

controlled by the valve member 103 which valve member seats with the pressure of the live air so that during periods of idleness the admission valve, which is in the form 5 of a puppet valve, is held tight against its seat by the pressure of the live air. Consequently there is a minimum tendency for air to escape over night or at other periods when the pump is idle. The exhaust port 104 is 10 controlled by the valve 105 which is connected directly to the operating piston 96 and the diaphragm 95. The valves 105 and 103 are connected together by means of the stem 106 and are properly guided by means 15 of the guide 107.

A spring 108 bears against the rear of the diaphragm 95 in order to balance the weight of the body of liquid 92 which bears upon the other side of the diaphragm.

20 The operation of this form is readily apparent. When the master valve 6 is operated to admit air to the pipe 91 at the top of the liquid 92, as by way of the pipe 7, the exhaust valve 105 is closed and the admission

25 valve 103 is opened against the pressure of the live air which operates to hold it against its seat when it is closed. This permits air to pass down the pipe 93 through the port 102, through the pipe 61 to the pump 1, driving

30 the water out of the cylinder of the pump by way of the pipe 4. As previously explained part of the water goes to the consumption system and part is accumulated in the auxiliary pumping device 3. When the auxiliary

35 pumping device is substantially filled with water the position of the master valve 6 is shifted to exhaust the pressure on top of the body of liquid 92 and this release of pressure permits the spring 108 to close the admission

40 valve 103 and to open the exhaust valve 105 permitting the compressed air in the pump to exhaust and the pump to fill with water from the well. At the same time the auxiliary pumping device 3 serves to supply 45 the consumption system until the pump is ready for the next stroke.

It is to be noted that in the event of a greater demand for water than the pump is able to supply or in any case where a 50 blow-over might occur, the diaphragm 16 will be forced to the extreme left causing the yielding valve member 19 to engage the seat 20 and to shut off any discharge from the pipe 4.

55 The capacity of the pump is so proportioned to the consumption system and to the auxiliary pumping device that even if the consumption system is opened to the maximum normal extent sufficient water from 60 each stroke will flow into chamber 14 to operate the valve 6. I have therefore shown the pipe 5 of smaller capacity than the pipe 4.

The auxiliary pumping device performs a 65 double function. It constitutes primarily

an "air spring" for equalizing the flow of water in the consumption system, particularly at the outlets. It constitutes also a stroke responsive device for operating the valves of the pump cylinder. The column 70 of water between the device 3 and the pump cylinder 1 is a direct inelastic connection. The quantity of water forced into the chamber 14 governs the operation of the valve 6.

The device 3 is subject to a further effect, 75 namely the opening and closing of the faucets of the consumption system. Opening of a faucet reduces the quantity of water in the chamber 14. As explained when the water has been reduced to a predetermined 80 minimum in the chamber such withdrawal causes operation of the valve 6. Similarly closing the faucets causes more water to be forced into the chamber 14 and the master valve 6 is accordingly operated. The broad 85 aspect of my invention is not necessarily limited to a submerged pump cylinder. It will be noticed that when the faucets are all closed the pump chamber 1 is open to exhaust and is not under pressure. The auxiliary pumping chamber is always under pressure. If a stroke of the main chamber is initiated and the full discharge of the same is not required the liquid is all discharged into the auxiliary chamber, filling 90 the same to the predetermined maximum condition and then the main chamber is connected to exhaust. Thus the pump may make short or long strokes in accordance with the demand for water. I consider that 100 I am the first to employ a chamber of variable capacity having a valve controlling the strokes of the pump according to the quantity of fluid contained in the chamber.

I claim:

1. In a system of the class described, a pump comprising a single cylinder having liquid inlet and outlet check valves, a discharge pipe and an air pipe, a source of compressed air communicating with the air 110 pipe, a master valve means above the level of the liquid controlled by the discharge of liquid from the cylinder, and a relay in the well adjacent to the pump cylinder controlling the inlet of air from said source 115 through the pipe to the pump cylinder, and means governed by the master valve for operating the relay valve.

2. In combination, a single pump cylinder having inlet and outlet check valves for liquid, a closed distributing system having delivery outlets, a source of motive fluid for the cylinder, a steady flow chamber communicating with the distributing system, said steady flow chamber being of sufficient 125 capacity to provide the full discharge from the system between strokes of the pump, a motor operated by the liquid flowing into and out of said steady flow chamber, and a valve operated by the motor controlling the 130

admission and exhaust of the fluid to and from the cylinder.

3. In combination, a single pump cylinder adapted to be submerged in the liquid, said 5 pump cylinder having liquid inlet and discharge check valves, a discharge passage, a closed distributing system having delivery outlets connected to said discharge passage, a motive fluid pipe for admitting and 10 exhausting fluid to and from the pump cylinder, a steady flow chamber at the head of the well communicating with said discharge passage, said steady flow chamber being of sufficient capacity to provide the full discharge 15 from the system between strokes of the pump and valve means controlled from said chamber for controlling the admission of motive fluid to the pump cylinder for each stroke of the pump.

20 4. In combination, a pump cylinder having liquid inlet and discharge check valves, a liquid discharge pipe, an air pipe for admitting and exhausting motive fluid, a source of compressed air, a diaphragm chamber having a diaphragm, said diaphragm chamber comprising a liquid cylinder on one side and an air cylinder on the other side of the diaphragm, a valve for controlling the air pipe of the cylinder and a connection 25 between the diaphragm and the valve.

5. In combination, a pump cylinder having liquid inlet and outlet check valves, a discharge pipe, an air pipe, a valve controlling said air pipe, a source of compressed 30 air for said air pipe, a closed system comprising a distribution pipe having manually controlled delivery outlets, a liquid accumulating cylinder having unrestricted communication with the distributing pipe and 35 the discharge pipe, a piston for said cylinder, means for opposing the movement of said piston and means operated by movement of said piston for controlling said air valve.

40 6. In combination, a single cylinder pump having a foot valve, an outlet check valve, a liquid discharge pipe, a closed distributing system having manually operable delivery outlets controlling the operation of the 45 pump, an air pipe communicating with the interior of the cylinder, a valve at the head of the well controlling the admission of air to the pump through said pipe, and means operated by the flow of liquid out of said 50 liquid discharge pipe for operating said valve for each stroke of the pump, said means being adapted to provide a discharge for the closed distributing system between strokes of the pump.

60 7. In combination, a single cylinder pump adapted to be submerged at the bottom of a well, said pump having a foot valve and an outlet check valve, a discharge pipe connected to said check valve, an air pipe communicating with the interior of the pump

cylinder for admitting compressed air, a control valve in the well adjacent said pump for controlling said pipe, a master valve at the head of the well, said master valve being controlled by the flow of liquid in said 70 discharge pipe, and operating means for the control valve governed by the master valve.

8. In combination, a single pump cylinder adapted to be submerged in the liquid of a well, said pump cylinder having inlet and 75 outlet valves, a discharge pipe, a valve in the well adjacent said pump cylinder, a valve at the head of the well, said last named valve being controlled by the flow of liquid in said discharge pipe, and an operating 80 element at the head of the well, said operating element having a movable element connected by a rigid connection to the valve at the bottom of the well for operating the same.

9. In combination, a single pump cylinder adapted to be submerged in the liquid of a well, said cylinder having a discharge pipe, an air pipe for admitting and exhausting air from the cylinder, a valve at the foot of the well adjacent said pump cylinder for controlling said air pipe, means for conducting compressed air to said controlling valve, a master valve at the head of the pump, a steady flow chamber having pressure controlled means for operating said controlling valve, said means comprising a non-expansible connection between the head and the foot of the well.

10. In combination, a pump cylinder submerged in the liquid at the bottom of the well, a discharge pipe from the cylinder, an auxiliary pumping device comprising a movable diaphragm at the head of the well, said diaphragm being affected by the discharge 100 of liquid from the pump cylinder, a master valve operated by said diaphragm, an air pipe for the pump cylinder, means for conducting compressed air downward to the foot of the well, a control valve at the foot 110 of the well, an operating element controlled by the master valve for operating said control valve, said operating element having a non-compressible member running from the head of the well to the foot of the well.

11. In combination, a pump cylinder adapted to be submerged in the liquid at the foot of the well, a diaphragm chamber at the head of the well, an air spring for the diaphragm, a master valve controlled by the 120 diaphragm, an operating cylinder and piston at the head of the well, a controlling valve at the foot of the well, a pipe for conducting compressed air to said controlling valve and a rod connecting said operating 125 piston with the valve at the foot of the well.

12. In a device of the class described, a pump cylinder adapted to be submerged in the liquid at the bottom of the well, a discharge pipe leading up from said cylinder,

85

90

95

100

105

110

115

- an air pipe leading from said cylinder, a union at the top of said air pipe, said union comprising a threaded portion surrounded by a funnel shaped portion, a pipe having 5 a valve member, said valve member having a portion adapted to engage said threads and to be guided to said threads by said funnel shaped member.
13. In combination, a pump cylinder, an air pipe for said pump cylinder, said pump cylinder being adapted to be submerged in the liquid in the bottom of the well, a controlling valve at the foot of the well adjacent said pump cylinder, said controlling 10 valve comprising a compressed air inlet port and an exhaust port and movable valve members for opening and closing said ports, said valve members having a lost motion connection between them, a rod connected to 15 said valve members and running to the head of the well, an operating piston at the head of the well, a pipe surrounding said operating piston, an operating cylinder supported on said pipe and means for admitting compressed air to each side of the operating 20 piston.
14. In a pump, a cylinder adapted to be submerged in the liquid at the bottom of the well, a discharge pipe and an air pipe, a controlling valve at the foot of the well adjacent said pump cylinder, an operating 25 element at the head of the well, said operating element comprising a cylinder and a piston, a pipe running between the operating cylinder and the controlling valve, means for supplying compressed air to said pipe, a rod running between said piston and the controlling valve, and a spring connection between the piston and the rod.
15. In combination, a pump cylinder adapted to be submerged in the liquid at the bottom of the well, a discharge pipe, an air pipe, a controlling valve at the foot of the well governing said air pipe comprising 30 axially arranged admission and exhaust valves, a lost motion connection between said valves, means for supplying air under pressure to said valve, and an operating piston at the head of the well for controlling 35 said control valve.
16. In combination, a pump cylinder adapted to be submerged in the liquid at the bottom of the well, a discharge pipe for the pump cylinder, an air pipe for the pump cylinder, a controlling valve at the foot of the well adjacent the pump cylinder, said controlling valve having an inlet port and an outlet port axially in line with each other, an inlet valve member and an outlet valve 40 member, said members being connected together by a lost motion connection, an operating cylinder having a piston at the head of the well, a rod connected to the controlling valve at the foot of the well and a 45 spring connection joining the rod and the piston at the head of the well.
17. In combination, a pump cylinder adapted to be submerged in the liquid at the bottom of the well, a liquid discharge pipe from said pump cylinder, an air pipe 50 for the pump cylinder, an auxiliary pumping device connected to the discharge pipe at the head of the well, a valve at the foot of the well adjacent the pump cylinder for admitting compressed air to and exhausting 55 the same from the pump cylinder by way of the air pipe and means controlled by the auxiliary pumping device for operating said valve.
18. In combination a pump cylinder having liquid inlet and discharge valves, a liquid discharge pipe leading to the head of the well, a control valve for controlling the admission and exhaust of compressed air to the pump cylinder, said valve being located 60 exteriorly of the pump cylinder but adjacent thereto, an auxiliary pumping device comprising a cylinder and a piston connected to said liquid discharge pipe, means for yielding opposing movement of said piston 65 and means controlled by movement of said piston for operating the control valve for the pump.
19. In a device of the class described, a liquid cylinder, an air cylinder, a diaphragm 70 dividing said cylinders, means for discharging water in the liquid cylinder, means for maintaining a fluid under pressure in said air cylinder, a valve port governing the admission of liquid to the water cylinder and 75 a valve member secured to the diaphragm for closing off said port in the event of the failure of liquid pressure in the liquid cylinder.
20. In combination, a liquid cylinder, an air cylinder, a piston member between said cylinders, a pump for discharging liquid into said water cylinder, a valve controlled by said piston governing the operation of said pump, and means for maintaining a 80 body of air under pressure in said air cylinder.
21. In combination, a liquid cylinder, an air cylinder, a diaphragm and piston subject to the pressure of fluids in said cylinders, a 85 valve casing mounted on one of said cylinders, a rod connected to said piston and projecting through the valve casing, a movable valve member and a loose connection between said valve member and said rod.
22. In combination, a liquid cylinder, an air cylinder, a piston responsive to pressure of fluids in said cylinder, a valve casing mounted on one of said cylinders, a rod projecting axially from said piston into the 90 valve casing, a movable valve member, a snap action operating lever connecting said rod with said valve member and means con-

- trolled by said valve member for discharging liquid into the liquid cylinder.
23. In combination, a chamber of variable capacity, a pump discharging wholly into said chamber, a valve controlled by the quantity of fluid in the chamber governing the individual strokes of the pump.
24. In combination, a chamber having a yielding wall, means for forcing the wall inward, a pump discharging into the chamber and moving the wall outward for each stroke, and a valve operated by movement of the wall for governing the operation of the pump.
25. In combination, a chamber having a yielding wall, means for forcing the wall inward, a pump discharging into the chamber and moving the wall at each stroke, valve means governing the pump, said valve means being controlled by the wall to cause the pump to discharge into the chamber when the wall is moved inwardly, and a discharge pipe of less capacity than the pump communicating with the chamber.
26. In combination, a source of motive fluid, a single cylinder pump in the well, a master valve at the head of the well for governing admission and exhaust of motive fluid to and from the pump for each stroke of the pump, a relay valve at the foot of the well governed by said master valve, said relay valve controlling communication of the pump alternately with the source of motive fluid and with exhaust.
27. In combination, a single cylinder pump adapted to be placed in the water in the well, a source of motive fluid, admission and exhaust valve mechanism at the foot of the well, a pipe leading to the valve mechanism from the source of motive fluid, means at the head of the well actuated by discharge of liquid from the pump governing said valve mechanism at the foot of the well.
28. In combination, a single cylinder pump adapted to be placed in the water in the well, a source of motive fluid, admission and exhaust valve mechanism at the foot of the well, a pipe leading to the valve mechanism from the source of motive fluid, pressure operated means for operating said valve mechanism, and valve means at the head of the well actuated by discharge of liquid from the pump governing said pressure operated means.
29. In combination, a pump barrel having inlet and discharge valves, a discharge pipe from the pump, a piston chamber at the head of the well communicating with said discharge pipe, a closed distributing system having manually controlled delivery faucets communicating with the piston chamber, said piston chamber having a piston movable by the pressure of the discharged liquid and means governed by motion of said pis-
- ton governing admission to and exhaust 65 from the pump of motive fluid.
30. In combination, a pump barrel, an inlet check valve for permitting the entry of liquid, a discharge check valve for liquid, a discharge pipe communicating with said 70 discharge check valve, a chamber of variable capacity, communicating with the discharge pipe, resilient means for forcing liquid out of the chamber, a closed distributing system having manually operable delivery faucets 75 communicating with said chamber and valve means governed by the quantity of liquid in the chamber for controlling admission and exhaust of motive fluid to and from the pump barrel.
31. In combination, an air displacement pump comprising a pump barrel, an inlet check valve for liquid, a discharge check valve for liquid, a discharge pipe communicating with the discharge check valve, a 80 chamber of variable capacity communicating with the discharge pipe and adapted to store and hold a quantity of liquid under pressure when the delivery faucets are closed, a closed distributing system having manually operable delivery faucets communicating with said chamber, resilient means for causing a discharge of liquid from the chamber through the distributing system when the delivery faucets are opened and valve means 90 governed by discharge of liquid from the chamber for admitting motive fluid to the pump barrel.
32. In a pump, a casing having a chamber communicating with the source of fluid supply, means for admitting motive fluid to said chamber, a discharge pipe through which liquid is forced by said motive fluid, a casing having a chamber into which the liquid is forced, a distributing system having normally closed manually operable delivery faucets communicating with said chamber and a device within said casing adapted to be moved outwardly and inwardly as the liquid enters the same and escapes therefrom and means connecting said admitting means to cut off the supply of motive fluid when said device is in its outer position.
33. In combination, an air displacement pump comprising, a pump barrel having an 100 inlet check valve for liquid, a discharge pipe for liquid, a discharge check valve in said discharge pipe, a chamber of variable capacity communicating with the discharge pipe and adapted to store and hold under 110 pressure a quantity of liquid at each stroke, a closed distributing system having manually operable delivery outlets communicating with said chamber and valve means governed by the storage of liquid in said chamber for shutting off the supply of motive fluid to the pump barrel.
34. In combination, a pump barrel having

liquid inlet and discharge valves, a discharge pipe, a chamber of variable capacity communicating with the discharge pipe, means for resisting enlargement of said chamber, valve 5 means operated by enlargement and contraction of said chamber for exhausting and admitting motive fluid from and to the pump barrel, and a normally closed distributing system having manually operable delivery 10 outlets, governing the storage of liquid in said chamber.

35. In a pump, a pump barrel, inlet and discharge valves for liquid, a delivery pipe, a pressure motor, a normally closed delivery system communicating with the pressure motor, said system having manually operable delivery outlets, valve means for admitting and exhausting motive fluid to and from the pump controlled by said motor, 15 said motor being operated on one stroke by the accumulation of back pressure governed by said manually controllable delivery openings, said motor serving to trap under pressure, a quantity of liquid for immediate delivery 20 to the distributing system when the manually operable delivery openings are opened.

36. In combination, a pump barrel having liquid inlet and discharge check valves, a 30 delivery pipe for liquid, a pressure operated motor at the head of the well, communicating with said delivery pipe, a normally closed distributing system communicating with said motor, manually operable delivery 35 outlets for said system, said motor having means for storing a quantity of liquid under pressure when the outlets are closed, valve means governing the admission and exhaust of motive fluid to and from the pump barrel, 40 said motor and valve means being organized to shut off admission and open exhaust of the pump barrel when the delivery outlets are closed.

37. In combination, a pump cylinder, inlet 45 and discharge valves for liquid, admission and exhaust valve mechanism for motive fluid, a normally closed delivery system having manually operable outlets, means for receiving and storing a quantity of liquid 50 under pressure when the outlets are closed, said last means being adapted to operate the said valve mechanism to shut off admission and open the exhaust of the pump cylinder when the outlets are closed.

55. 38. In combination, a pump, a pressure delivery system, a steady flow chamber having a piston, resilient means pressing the piston inwardly, said pump, delivery system and chamber being connected together with- 60 out restriction, and valve means controlled by outward movement of the piston for connecting the pump to exhaust, said piston being held outwardly between strokes of the pump and until a definite quantity of liquid 65 is discharged from the system.

39. In combination, a pump, a pressure delivery system, a steady flow chamber for storing a definite quantity of liquid under pressure for furnishing the discharge between strokes of the pump, means operable 70 only when said definite quantity has been discharged for admitting motive fluid to the pump for the next discharge stroke, said means controlling the individual strokes of the pump. 75

40. In combination, a single cylinder pump barrel in the well having a liquid inlet and a liquid discharge check valve and an air port, a motor element at the head of the well controlled by the individual strokes 80 of the pump, a master valve at the head of the well operated by said motor element, and a relay valve controlled by the master valve, said relay valve governing the admission and exhaust of motive fluid to and 85 from the pump barrel.

41. In combination, a pump having inlet and discharge check valves, a faucet controlled delivery system for the pump, an auxiliary pumping chamber, said chamber furnishing the discharge for the delivery system between strokes of the pump, and a valve governed by the quantity of liquid in the auxiliary chamber governing admission and exhaust strokes of the pump. 95

42. In combination, a single cylinder pump, a closed delivery system for the pump, a steady flow chamber for the pump for maintaining a constant pressure on the delivery system, said chamber comprising a 100 movable piston communicating on one side only with the delivery system and a valve governed by said piston for governing admission and exhaust of motive fluid to and from the pump, said steady flow chamber 105 being of sufficient capacity to supply the discharge from the delivery system during the exhaust and filling period of the pump.

43. In combination, a single cylinder pump, a faucet controlled delivery system 110 for the pump, a steady flow chamber having means for maintaining a fluid pressure upon the fluid in said chamber for discharge, said chamber furnishing the discharge for the delivery system between strokes of the 115 pump, and a valve controlled by the fluid contents of said steady flow chamber governing admission and exhaust strokes of the pump.

44. In combination, a pump barrel adapted to be submerged in the liquid to be pumped, a steady flow chamber, a passageway connecting the pump and the steady flow chamber, said passageway having a check valve for preventing flow from the steady 120 flow chamber to the pump, valve means controlled by the water content of the steady flow chamber for governing the individual strokes of the pump, a delivery system communicating with the steady flow chamber, 125 130

and means controlled by emptying of the steady flow chamber for preventing air from being discharged from the pump into the steady flow chamber.

5 45. In combination, a single cylinder pump adapted to be submerged in the liquid, a steady flow chamber connected to the pump, a check valve for preventing flow of fluid from the steady flow chamber to the 10 pump, means controlled from the steady flow chamber governing the individual strokes of the pump, and means for closing the communication between the pump and the steady flow chamber when the steady flow 15 chamber is emptied.

46. In combination, a pump adapted to be submerged in the liquid to be pumped, a steady flow chamber, a pipe connecting the pump with the steady flow chamber, a 20 check valve governing said pipe, means for maintaining a pressure on the liquid in the steady flow chamber for providing a satisfactory pressure for discharge, and means for closing off the connection between the 25 pump and the steady flow chamber when the steady flow chamber is emptied.

47. In a device of the class described, a vertical pipe having a cylinder at its upper end, a piston in said cylinder, one side of 30 the cylinder being open to said pipe, means for admitting motive fluid to the pipe at all times, means for intermittently admitting motive fluid to the other end of the cylinder, a valve cage on the lower end of 35 the pipe, said valve cage having a central chamber adapted to communicate with a pneumatic pump, an admission port leading into said central chamber, and an exhaust port leading into said central chamber, and 40 valve means in the central chamber for obstructing said ports one at a time, said valve means being connected to the piston in the cylinder.

48. In a device of the class described, a vertical pipe having a cylinder at its upper end, a piston in said cylinder, one side of the cylinder being open to said pipe, means for admitting motive fluid to the pipe at all times, means for intermittently admitting 45 motive fluid to the other end of the cylinder, a valve cage on the lower end of the pipe, said valve cage having a central chamber adapted to communicate with a pneumatic pump, an admission port leading into said central chamber, and an exhaust 50 port leading into said central chamber, valve means in the central chamber for obstructing said ports one at a time, said valve means being connected to the piston in the cylinder, said valve casing member having a hollow tubular extension at its lower end adapted to be put in communication with a pump, said extension being threaded, and a 55 funnel shaped coupling member adapted to coöperate with said threads.

49. In combination, a main pump chamber, an auxiliary pump chamber, a passage-way for liquid connecting said chambers, a closed delivery system connected to said auxiliary chamber, motive fluid valve means for 70 admitting and exhausting motive fluid to and from the main pump chamber independently of the level conditions therein for each stroke of the pump, a pressure motor for operating said valve means for the individual strokes of the pump, a control valve operated in accordance with the quantity of liquid in the auxiliary pump chamber 75 said control valve governing said valve means.

50. In combination, a main pump chamber, an auxiliary pump chamber, a passage-way for liquid connecting said chambers, a closed delivery system connected to said auxiliary chamber, valve means for admitting 80 and exhausting motive fluid to and from the main pump chamber independently of the level conditions therein for the individual pump strokes, a pressure motor for operating said valve means, a control valve operated in accordance with the quantity of liquid in the auxiliary pump chamber 85 said control valve governing said valve means, and means for maintaining a predetermined minimum pressure on the liquid for discharge in the auxiliary chamber regardless 90 of the quantity therein, said auxiliary chamber being of sufficient capacity to supply the normal flow of liquid from the system during the filling period of the pump. 95

51. In combination, a main pumping chamber in the well, an auxiliary pumping chamber, a connection for liquid between the two chambers, a discharge system connected to the auxiliary chamber, a motive 100 fluid pipe extending from the head of the well down to the main chamber, said pipe and the main chamber having a readily disconnectible coupling in the well, admission and exhaust valves for motive fluid carried 105 by said pipe above said coupling, and a motor controlled from the auxiliary pumping chamber to operate the admission and exhaust valves.

52. In combination, a main pump chamber having inlet and discharge valves for liquid, an exhaust port, an exhaust valve adapted to close the exhaust port for each discharge stroke of the pump and being adapted to be held to its seat by the pressure 110 of the compressed air in the chamber, a fluid pressure motor for pulling the valve off seat against pressure, a control valve for the motor, an auxiliary pump chamber communicating with the main pump chamber 115 and means governed by the water in the auxiliary pump chamber for actuating said control valve.

53. In combination, a main pump chamber having water inlet and discharge valves, 120

an exhaust port for motive fluid, an exhaust valve, an admission port and an admission valve adapted to be held on its seat by pressure of the motive fluid before it enters the 5 pump chamber, an auxiliary pump chamber, a check valve connection between the two chambers, a motor for operating the admission and exhaust valves, and a control valve actuated when the auxiliary pump chamber 10 is full to open the exhaust valve and apply the admission valve to its seat.

54. In combination, a pump chamber having liquid inlet and discharge valves, a 15 source of motive fluid, main valve mechanism for controlling the admission and exhaust of motive fluid to and from the pump chamber, a motor for operating said main valve mechanism, and a pilot valve controlled by the discharge of liquid from the 20 pump chamber for governing said motor.

55. In combination, a pump chamber having liquid inlet and discharge valves, a 25 source of motive fluid, main valve mechanism for controlling the admission and exhaust of motive fluid to and from the pump chamber, a motor for operating said main valve mechanism, a pilot valve controlled by the discharge of liquid from the pump chamber for governing said motor, and means for 30 controlling the discharge of liquid from the pump chamber.

56. In combination, a single cylinder pump chamber having fluid inlet and discharge valves, a closed faucet controlled delivery 35 system, a steady flow chamber for receiving fluid at each stroke from the pump chamber, and valve mechanism controlling the admission and exhaust of motive fluid to and from the pump chamber, said valve 40 mechanism being responsive to the flow of fluid into and out of said steady flow chamber.

57. In combination, a single cylinder pump chamber having liquid inlet and discharge 45 valves, a closed faucet controlled delivery system, a steady flow chamber for receiving liquid at each stroke from the pump chamber, said steady flow chamber being of sufficient capacity to supply the normal 50 discharge of liquid from the system during the filling period of the pump chamber, and valve mechanism controlling the admission and exhaust of motive fluid to and from the pump chamber, said valve mechanism being 55 responsive to a predetermined accumulation of liquid in the steady flow chamber to cut off the motive fluid and connect the pump chamber to exhaust.

58. In combination, a single cylinder pump 60 having liquid inlet and discharge valves, and admission and exhaust valves for motive fluid, a closed faucet controlled system and a steady flow chamber connected to said system, said steady flow chamber having means 65 controlled both by the discharge of liquid

from the pump and by the discharge of water from the steady flow chamber for controlling the admission and exhaust valves for the individual strokes of the pump, said steady flow chamber being of sufficient capacity to supply the normal discharge of liquid from the system during the filling 70 strokes of the pump.

59. In combination, a primary pumping chamber and an auxiliary pumping chamber both connected to a closed delivery system, means for maintaining a substantially constant pressure on the liquid in the system, said means having connection with the auxiliary pumping chamber, the primary pumping chamber having means for intermittently injecting liquid into the auxiliary pumping chamber and valve means controlled by the pressure maintaining means of the auxiliary chamber for governing the application of 80 motive fluid to operate the primary pumping chamber, said auxiliary pumping chamber being of sufficient capacity to provide the normal discharge of liquid from the delivery system during the filling period of the primary pumping chamber. 90

60. In combination, a primary pumping chamber and an auxiliary pumping chamber both connected to a closed delivery system, means for maintaining a substantially constant pressure on the liquid in the system, said means operating on the liquid in the auxiliary pumping chamber, the primary pumping chamber having means for intermittently injecting liquid into the auxiliary pumping chamber, and means controlled by the accumulation of a predetermined quantity of liquid in the auxiliary pumping chamber to disconnect the primary pumping chamber from the source of motive fluid, said auxiliary pumping chamber being of sufficient capacity to supply the normal discharge of liquid from the system during the filling stroke of the primary pumping chamber. 100 105 110

61. In combination, a primary pumping chamber and an auxiliary pumping chamber both connected to a closed faucet controlled delivery system, means for maintaining a substantially constant pressure on the liquid in said auxiliary pumping chamber the primary pumping chamber having valve means governing the individual strokes of the same for injecting water into the auxiliary pumping chamber and means controlled by the accumulation of a predetermined quantity of liquid in the auxiliary pumping chamber to connect the primary chamber to exhaust, said auxiliary pumping chamber being of sufficient capacity to 115 provide the normal delivery of liquid from the system during the filling stroke of the primary pumping chamber. 120 125

62. In a faucet controlled system, a pump chamber having liquid inlet and discharge 130

- valves, a discharge passageway communicating with a closed delivery system, a steady flow chamber communicating with the closed system, said steady flow chamber having 5 motor means operated in accordance with the discharge of liquid to and from the steady flow chamber and valve mechanism operated by the motor means and controlling the admission and exhaust of motive fluid to and from the pump chamber, said steady flow chamber being of sufficient capacity to provide the normal discharge of liquid from the system during the filling stroke of the pump chamber.
- 10 63. In a faucet controlled system, a pump chamber having liquid inlet and discharge valves, a discharge passageway communicating with a closed delivery system, a steady flow chamber communicating with the closed system, motor means for said steady flow chamber actuated when the liquid in the steady flow chamber has reached a predetermined minimum, and a valve operated by said motor governing the admission of motive fluid to the pump chamber, said steady flow chamber being of sufficient capacity to provide the normal discharge of liquid from the system while the pump chamber is filling.
- 15 64. In a device of the class described, a pump chamber having liquid inlet and discharge valves, a discharge passageway communicating with a closed system, a steady flow chamber communicating with the system, a motor for said steady flow chamber actuated when the liquid in the steady flow chamber has reached a predetermined maximum, and a valve operated by said motor governing the exhaust of motive fluid from the pump chamber, said steady flow chamber being of sufficient capacity to provide the normal discharge of liquid from the system while the pump chamber is filling.
- 20 65. In combination, a pump barrel, a steady flow chamber, a closed discharge system communicating with the steady flow chamber, an unrestricted communication from the pump barrel to the steady flow chamber, and a valve controlled by the quantity of liquid in the steady flow chamber, governing the individual strokes of the pump, said steady flow chamber being of sufficient capacity to provide the normal discharge of liquid from the system during the filling stroke of the pump barrel.
- 25 66. In combination, a single cylinder pump for receiving liquid and discharging the same in intermittent strokes, a source of motive fluid, a closed delivery system, a tank communicating with the pump and with the closed system, said tank being adapted to receive liquid during the discharge stroke of the pump whether the delivery system is open or closed, and to discharge liquid into the delivery system dur-
- 30 35 40 45 50 55 60 65
- ing filling strokes of the pump only when the delivery system is opened, and means responsive to the filling of the tank for disconnecting the source of compressed air and connecting the pump to exhaust, said tank 70 being of sufficient capacity to supply the normal discharge of liquid from the system during the filling strokes of the pump.
67. In combination, a single cylinder pump for receiving liquid and discharging the same 75 in intermittent strokes, a source of motive fluid, a closed delivery system, a tank communicating with the pump and with the closed system, said tank being adapted to receive liquid during the discharge stroke 80 of the pump whether the delivery system is open or closed and to discharge liquid into the delivery system during filling strokes of the pump only when the delivery system is opened, and means responsive to the low 85 content condition of the tank for closing the exhaust valve and connecting the source of motive fluid to the pump, said tank being of sufficient capacity to supply the normal discharge of liquid from the system during the 90 filling strokes of the pump.
68. In a device of the class described, a pump chamber in the well having inlet and discharge check valves for liquid, an exhaust port, an exhaust valve held to its seat by the pressure in the pump chamber to close said port, a fluid pressure motor for pulling the exhaust valve from its seat against the pressure, and control means for the fluid pressure motor at the head of the well and independent of the level of liquid in the chamber.
- 95 70. In combination, a pump chamber having liquid check valves, an exhaust port and an exhaust valve adapted to be held on its seat by the pressure within the pump chamber, a fluid pressure motor for opening the exhaust valve against pressure, a steady flow chamber connected to the pump chamber, and a valve controlled by the quantitative condition of the liquid in the steady flow chamber for governing the operation of the motor to operate the exhaust valve for each stroke of the pump.
- 100 105 110 115 120 125 130
71. In combination, a single cylinder pump chamber in the well having check valves for liquid inlet and discharge, a steady flow chamber connected to the pump chamber, an exhaust port for the pump chamber adjacent the head of the pump, an exhaust valve adapted to be held to the port by pressure within the pump chamber, a motor element at the head of the well, said motor element having a cylinder rigidly connected with the head of the pump, and a piston connected to the exhaust valve, said piston moving in the cylinder.

- head of the pump, an exhaust valve adapted to be held to the port by pressure within the pump chamber, a motor element adjacent to the head of the well, said motor element having a cylinder rigidly connected with the head of the pump, a piston connected to the exhaust valve, said piston moving in the cylinder, and spring means interposed between the piston and the exhaust valve for throwing the exhaust valve away from its seat after said valve has started to open. 70
72. In combination, a single cylinder pump chamber in the well, a steady flow chamber connected to the pump chamber, an exhaust port for the pump chamber adjacent the head of the pump, an exhaust valve adapted to be held to the port by pressure within the pump chamber, a motor element adjacent the head of the well, said motor element having a cylinder rigidly connected with the head of the pump, a piston connected to the exhaust valve, said piston moving in the cylinder, and means for throwing the exhaust valve away from its seat after the valve has started to open, said piston and said exhaust valve having a lost motion connection. 75
73. In combination, a pump having water inlet and discharge check valves, a closed delivery system for the pump, a diaphragm chamber communicating with the discharge system, said chamber having a fluid pressure operable diaphragm, a compressed air pipe leading to the pump, an air valve governed by said diaphragm for shutting off the compressed air, and means for throwing the valve suddenly from open to closed position. 80
74. In combination, a pump having water inlet and discharge valves, a water discharge pipe connected to a closed delivery system, a compressed air supply pipe for the pump, a fluid pressure motor operated by the discharge of water from the pump into the closed delivery system when the system is completely closed, and a valve operated by the motor for shutting off the supply of compressed air from the pump, said valve and motor having means for throwing the valve positively and quickly from one position to another, independently of the rate of water discharge from the pump into the system. 85
75. In combination, a pneumatic pump having check valves for admission and discharge of liquid, a source of compressed air for the pump, a closed delivery system, a closed tank connected to the system, a yielding member connected to the tank and a motive fluid admission valve controlled by the yielding member when a predetermined amount of water is in the tank for shutting off the source of motive fluid at each stroke of the pump. 90
76. In combination, a pneumatic displacement pump cylinder, a source of compressed
- air for the pump cylinder, a closed delivery system, a closed tank connected to the system, a yielding member connected to the tank, a valve controlled by the yielding member when a predetermined amount of water is in the tank for shutting off the source of compressed air from the pump cylinder, said valve having means for suddenly throwing the valve to closed position independently of the rate of movement of the yielding member and connecting said chamber to exhaust. 95
77. In combination, a main pneumatic displacement pump chamber, a water discharge passageway, a source of motive fluid, a valve for motive fluid, an auxiliary pump chamber and a closed water delivery system connected to the discharge passageway, said auxiliary pumping chamber being of sufficient capacity to provide the normal discharge for the delivery system during the filling strokes of the main chamber, a motor member operated by the discharge of a predetermined amount of water from the main pump chamber into the auxiliary chamber to operate said valve to cut off the supply of compressed air from the main chamber. 100
78. In combination, a main pneumatic displacement pump chamber, a water discharge passageway, a source of motive fluid, a valve for motive fluid, an auxiliary pump chamber and a closed water delivery system connected to the discharge passageway, a motor member operated by the discharge of a predetermined amount of water from the main pump chamber into the auxiliary chamber to operate said valve to cut off the supply of compressed air from the main chamber, and a snap action mechanism for throwing the valve positively to closed position. 105
79. In combination, a main pump chamber, a water discharge passageway, a source of motive fluid, a valve for motive fluid, an auxiliary pumping chamber and a closed water delivery system connected to the discharge passageway, said auxiliary pumping chamber being of sufficient capacity to provide the discharge from the delivery system during the filling stroke of the main pump chamber, a motor member operated by the discharge of a predetermined amount of water from the auxiliary pumping chamber through the delivery system to operate the valve to admit compressed air to the main pump chamber for each stroke of the pump. 110
80. In combination, a pump chamber, a source of compressed air, a motor cylinder, a piston in the cylinder, means for admitting compressed air at all times on one side of the piston, means for admitting and exhausting compressed air on the other side of the piston to control the individual pump strokes, a valve device having puppet type valve members for controlling admission 115
- 125
- 130
- 135

and exhaust of the compressed air to and from the pump chamber.

81. In combination, a pump chamber, a source of compressed air, a motor cylinder, 5 a piston in the cylinder, means for admitting compressed air at all times on one side of the piston, means for admitting and exhausting compressed air on the other side of the piston to control the individual pump 10 strokes, a valve device having puppet type valve members for controlling admission and exhaust of the compressed air to and from the pump chamber, one of the valve members being held to its seat by the pressure 15 of the compressed air thereupon.

82. In combination, a pumping chamber, a source of compressed air, a motor cylinder, a piston in the cylinder, means for admitting compressed air at all times on one side 20 of the piston, means for admitting and exhausting compressed air on the other side of the piston to control the individual pump strokes, a valve device having puppet type valve members for controlling the admission 25 and exhaust of the compressed air to and from the pump chamber, said valve members having a lost motion connection between them, and a spring connecting the piston and valve device.

83. In combination, a pumping chamber, a source of compressed air, a motor cylinder, a piston in the cylinder, means for admitting compressed air at all times on one side 35 of the piston, means for admitting and exhausting compressed air on the other side of the piston to control the individual pump strokes, a valve device having puppet type valve members for controlling the admission and exhaust of the compressed air to and 40 from the pump chamber, said exhaust valve member being held to seat by the pressure of the air thereupon.

84. In combination, a pumping chamber, a source of compressed air, a motor cylinder, 45 a piston in the cylinder, means for admitting compressed air at all times on one side of the piston, means for admitting and exhausting compressed air on the other side of the piston to control the individual pump 50 strokes, a valve device having puppet type valve members for controlling the admission and exhaust of the compressed air to and from the pump chamber, said exhaust valve member being held to seat by the pressure of 55 the air thereupon, said piston having means at one end for decreasing the area subjected to pressure at one end of the stroke.

85. In combination, a pump chamber, a source of compressed air, a motor cylinder, 60 a piston in the cylinder, means for admitting compressed air at all times on one side of the piston, means for admitting and exhausting compressed air on the other side of the piston to control the individual pump 65 strokes, a valve device having puppet type

valve members for controlling admission and exhaust of the compressed air to and from the pump chamber, said puppet valve members lying in line with each other, a valve casing having a central chamber communicating with the pump chamber and having admission and exhaust ports in line with the valve members, said admission port communicating with said one side of the piston.

86. In combination, a pneumatic displacement pump chamber connected to a closed discharge system having an auxiliary pumping device, said discharge system and auxiliary pumping device being always maintained under pressure, said pump chamber being adapted when no water is discharged from the system to be disconnected from the motive fluid and connected to exhaust, a compressed air admission valve governing the application of pressure to the pump chamber for the individual strokes thereof, said valve being adapted to be held to seat by the pressure of the compressed air thereupon, and a motor controlled by the discharge of water from the closed system to open said valve against the pressure of the motive fluid.

87. In combination, a pneumatic pump chamber connected to a closed discharge system having an auxiliary pumping device, said system and said auxiliary pumping device being always maintained under pressure, said pump chamber being adapted when no water is discharged from the system to be disconnected from the motive fluid and connected to exhaust, a compressed air admission valve and a motor piston operated by the motive fluid to hold the admission valve positively to seat.

88. In combination, a closed delivery system, a pneumatic pump chamber adapted to fill with liquid when no water is being drawn from the system, an auxiliary pumping chamber in communication with the delivery system constantly under pressure and having means controlling the application of motive fluid to the pump chamber after a predetermined amount of liquid has been drawn from the auxiliary pumping chamber.

89. In a system of the class described, a pump barrel adapted to be submerged in the liquid in the well, a water discharge pipe running from the barrel to the head of the well, a motor element at the head of the well controlled by the liquid discharged at each stroke of the pump, a motive fluid pipe running from the head of the well to the pump barrel, a valve for said latter pipe governed by said motor for controlling the admission and exhaust of motive fluid to and from the pump barrel and a releasable coupling in the well adjacent the pump operable from the head of the well for permitting the separation of the motive fluid pipe.

and leaving the pump in the liquid in the well.

90. In a system of the class described, a pump barrel adapted to be submerged in the liquid in the well, a water discharge pipe running from the barrel to the head of the well, a motor element at the head of the well controlled by the liquid discharged at each stroke of the pump, a motor fluid pipe running from the head of the well to the pump barrel, a valve for said latter pipe governed by said motor for controlling the admission and exhaust of motive fluid to and from the pump barrel and a releasable coupling in the well adjacent the pump operable from the head of the well for permitting the separation of the motive fluid pipe and leaving the pump in the liquid in the well, said coupling having a flaring guide to permit of easy connection of the motive fluid pipe.

91. In combination, a main pump chamber in the liquid, an auxiliary pump chamber above the liquid, a connecting passageway for liquid having a check valve for preventing the flow of water from the auxiliary chamber back to the main chamber, a motor having a movable element subject to the pressure of the liquid discharged from the main pump chamber and a control valve governing the admission and exhaust of motive fluid to and from the pump for the individual strokes thereof, said valve being operated by said motor, said auxiliary pumping chamber being of sufficient capacity to supply the discharge during the filling stroke of the main pump chamber.

92. In combination, a main pumping chamber, an auxiliary pumping chamber, a check valved passageway between them, means for admitting pressure to the main chamber to drive the liquid from the main chamber into the auxiliary chamber, and means controlled by filling of the auxiliary chamber for releasing the pressure on the main chamber to permit the main chamber to fill, said means comprising a pressure operated motor and a valve for motive fluid, said auxiliary pumping chamber being of sufficient capacity to provide discharge while the main pumping chamber is filling.

93. In combination, a pump chamber having liquid inlet and discharge valves and motive fluid inlet and exhaust ports, valve means for alternately obstructing said ports, an auxiliary chamber, a liquid discharge passageway between the pump chamber and the auxiliary chamber, means operated by the pressure in the auxiliary chamber when the same is filled for controlling said valve means, to obstruct the inlet port and open the exhaust port at each stroke of the pump, said auxiliary chamber being of sufficient capacity to provide the liquid discharge during the filling period of the pump chamber.

94. In combination a main pump cham-

ber, an auxiliary pump chamber, a closed delivery system connected to the auxiliary chamber, valve means adjacent the main chamber for admitting and exhausting pressure to and from the main chamber, a motive fluid pressure pipe leading to said main chamber and controlled by said valve means, a liquid column and a motor element operated by said liquid column for operating said valve means and a valve device governed by filling of the auxiliary chamber with liquid from the main chamber for applying pressure to the liquid column to actuate said motor element.

95. In combination, a closed delivery system, a main pumping chamber submerged in the liquid to be pumped, liquid inlet and discharge valves for said chamber, an auxiliary pumping chamber above the liquid, a passageway connecting the main chamber with the auxiliary chamber, said auxiliary chamber having a yielding member subjected to pressure within the auxiliary chamber, a motive fluid admission and exhaust valve for the main chamber controlled by said yielding member for admitting and exhausting motive fluid to and from the main chamber at each stroke of the pump, said auxiliary chamber having means for expelling liquid therefrom in sufficient quantity to provide the discharge from the system during the filling of the main chamber.

96. In combination, a closed delivery system having normally closed outlets, a main pumping chamber submerged in the liquid to be pumped, liquid inlet and discharge valves for said chamber, an auxiliary pumping chamber above the liquid, a connection between the main chamber and the auxiliary chamber, a motive fluid admission and exhaust valve for the main chamber for admitting and exhausting motive fluid to and from the main chamber for each stroke of the pump, and a pressure operated motor element for said valve, controlled by filling and emptying of the auxiliary chamber, said auxiliary chamber having means operated by motive fluid for expelling liquid therefrom between filling strokes of the main chamber.

97. In combination, a closed delivery system having normally closed outlets, a main pumping chamber in the liquid and an auxiliary pumping chamber above the liquid, said chambers being connected together for supplying liquid to said system, a main motive fluid valve for admitting and exhausting motive fluid to and from the main pumping chamber for each stroke of the pump, means for discharging the liquid from the main chamber when the outlets are closed only into the auxiliary chamber, and means governed by filling of the auxiliary chamber when said outlets are closed for operating the valve to connect the main chamber to exhaust until the liquid in the auxiliary

chamber drops to a predetermined minimum and means for maintaining pressure by motive fluid upon the liquid in the auxiliary chamber while the main chamber is connected to exhaust.

98. In combination, a pump having inlet and discharge check valves for liquid, a closed delivery system for the pump, a chamber communicating with the discharge system on said chamber having a fluid pressure operable member, a source of motive fluid for the pump, a valve governed by said member for shutting off the motive fluid, and means controlled by the member for throwing the valve suddenly from open to closed position.

99. In combination, a pneumatic pump chamber connected to a closed discharge system having an auxiliary pumping device, said system being always maintained under pressure, said pump chamber being adapted when no water is discharged from the system to be disconnected from the motive fluid and connected to exhaust, a compressed air admission valve and a motor piston operated by the motive fluid to hold the admission valve positively to seat, said auxiliary pumping device being of sufficient capacity to provide a satisfactory discharge from the closed system during the filling period of the pump chamber.

100. In combination, a main pump chamber, an auxiliary pump chamber, a closed delivery system connected to the auxiliary chamber and constantly maintained under pressure, valve means adjacent the main chamber for admitting and exhausting pressure to and from the main chamber, a motive fluid pressure pipe leading to said main chamber and controlled by said valve means, a liquid column and a motor element operated by said liquid column for operating said valve means, and a valve device governed by the discharge of a predetermined quantity of liquid from the main chamber into the auxiliary chamber to actuate said main valve to apply pressure to the liquid column to actuate said motor element.

101. In a system of the class described, a pump barrel adapted to be submerged in the liquid to be pumped, a distribution system connected to the pump barrel, a motor element controlled by the liquid discharged at each stroke of the pump, a motive fluid pipe leading to the pump barrel, a valve for said latter pipe governed by said motor for controlling the admission and exhaust of motive fluid to and from the pump barrel and a releasable coupling in said pipe between said valve and said pump for permitting the removal of the motive fluid pipe and said valve and leaving the pump in the liquid in the well.

102. In combination, a pumping chamber having liquid inlet and discharge valves and

a main air valve for admitting and exhausting motive fluid to and from the pumping chamber, a closed system having outlets, and means governed by the difference in rate of flow between air and liquid to said outlet for stopping the operation of the pump when the liquid fails to fill the pump.

103. In combination, a single cylinder pump having liquid inlet and discharge valves and a main air valve for admitting and exhausting motive fluid to and from the pump, a normally closed system having a steady flow chamber, and means governed by emptying of the steady flow chamber for stopping the operation of the pump to prevent wastage of the motive fluid.

104. In combination, a pump having a head member, a passage through said head member for the discharge of water, another passage in the head member for admission and exhaust of motive fluid, a water discharge pipe connected to said first passage, an air pipe connected to said second passage, a union connected to said air pipe, said union having a flared top with a threaded opening, and a threaded member adapted to connect to said union, said union being guided by said flared top.

105. In apparatus of the character set forth, the combination of a cylinder into which the fluid to be lifted enters, and means for alternately introducing fluid-pressure into said cylinder to force the fluid therefrom, and venting said cylinder of the contained fluid pressure following the fluid-lifting operation comprising a longitudinally movable valve-device, a piston and cylinder device operating said valve device, and means coöperating with the movable element of said piston and cylinder device for presenting to the movement of the latter an overcomable resistance near the end of its stroke only.

106. In apparatus of the character set forth, the combination of a cylinder into which the fluid to be lifted enters, and means for alternately introducing fluid-pressure into said cylinder to force the fluid therefrom, and venting said cylinder of the contained fluid pressure following the fluid-lifting operation comprising a longitudinally movable valve-device, a piston and cylinder device operating said valve device, and means coöperating with the movable element of said piston and cylinder device for presenting to the movement of the latter an overcomable resistance near the end of its stroke only, in opposite directions.

107. In apparatus of the character set forth, the combination of a cylinder into which the fluid to be lifted enters, and means for alternately introducing fluid-pressure into said cylinder to force the fluid therefrom, and venting said cylinder of the

contained fluid-pressure following the fluid-lifting operation comprising a longitudinally movable valve-device, a piston and cylinder device operating said valve device, and spring means cooperating with the movable element of said piston and cylinder device for presenting to the movement of the latter an overcomable resistance near the end of its stroke only.

10 108. In combination, a single cylinder

pump having inlet and discharge check valves and adapted to be submerged in the liquid to be pumped, an air spring connected to said pump, and means controlled by the amount of liquid in the air spring for controlling the admission of and exhaust of motive fluid to and from the pump. 15

In witness whereof, I hereunto subscribe my name this 20th day of July, A. D. 1917.

BURTON S. AIKMAN.
